UNITED STATES PATENT OFFICE.

DANIEL M. WINANS, OF BINGHAMTON, NEW YORK, ASSIGNOR TO THE BREWER-TITCHENER CORPORATION, OF BINGHAMTON, NEW YORK, A CORPORATION OF NEW YORK.

CURTAIN LIGHT.

Application filed May 4, 1923. Serial No. 636,594.

To all whom it may concern:

Be it known that I, DANIEL M. WINANS, a citizen of the United States, residing at

Binghamton, in the county of Broome and 5 State of New York, have invented certain new and useful Improvements in Curtain Lights, of which the following is a specification.

This invention relates to that class of vehicle curtain "lights" employing complementary inner and outer metallic frames detachably secured together, which grip the fabric of the curtain and the window pane or "light" between them. Various constructions of light holding frames of this general class are now known to the art, being particularly adapted for use on the tops and curtains of automobiles.

Some automobile tops have linings, while others are unlined; some have large and heavy windows and lights, while others, particularly on the more moderately priced cars, employ panes which are of lighter weight.

While not restricting the present invention to weights or dimensions, it is, nevertheless, more particularly adapted for use in connection with curtains where the purpose is not to "blind in" or cover the pane holding means as is desired on high priced automobiles but where the desideratum is the provision of a light, strong, durable, and relatively inexpensive pane or window holder which may be quickly and easily applied to the curtain, or removed therefrom when a new pane has to be substituted, having novel means for gripping the curtain fabric in such manner that puckering, slippage, or pulling out of the fabric from the frame will be prevented; further, to provide improved stops or abutments for the edge of the pane; and to make provision for "packing" the joint between the pane and the frames; also, to provide an ornamental outer frame, combined with the clamping or holding frames in an improved manner by means of spaced tapered screw fastening means.

The endless frames constituting the curtain light holder are sheet metal stampings, thus permitting their production at minimum expense and assuring perfect interchangeability with substitute, corresponding frames when necessary as also afford-

ing the requisite degree of springiness to 55 effect clamping action on the pane and on the fabric.

The outer frame is preferably corrugated and made into a cross-sectionally bowed or dished shape having both of its longitudinal edges inturned. An inset strip adapted to span or subtend this bowed profile, is clinched between the respective inturned edges for the purpose of imparting augmented rigidity and strength to the frame 60 structure.

A further feature of the present invention resides in the form and cooperation of the frames where they engage the curtain fabric, the arrangement and combination of parts being such that a "snubbing" 70 action results which prevents puckering, displacement, or pulling out of the fabric.

While it is preferable to employ resilient packing, for instance tubular packing, between the inset strip and the pane to cushion the clamping action of the frame and afford a maximum water-proofing of the joint, nevertheless such packing is not essential and may be dispensed with but it 75 is preferable to provide the frames with certain corrugations to prevent buckling and to afford requisite strength without detracting from the resilient grip of the frames on the pane as well as to enable the 80 frames to grip the pane inwardly from the margin thereof and thus minimize possibility of chipping or breaking the pane.

It will be understood that modifications 85 may be resorted to in carrying out the principle of the invention which is not restricted to the exact details hereinafter described and which are shown in the accompanying drawings, except as specifically set forth in the claims.

In the accompanying drawings:

Figure 1 is a view looking toward the outside of the curtain light, certain parts being broken away to better illustrate the construction.

Fig. 2 is a view looking toward the inside of the light, parts being broken away.

Fig. 3 is a detail sectional perspective view showing the construction and action of the frames; and

Fig. 4 is a detail cross section of the construction shown in Figs. 1, 2 and 3, the packing being omitted.

The glass pane or "light" is shown at 1 and the curtain fabric at 2.

As is shown in Figs. 3 and 4, the outer sheet metal finishing frame member 9 is provided with a cross-sectionally bowed shaped profile of which both longitudinal edges are first slightly bent outwardly and away from the dished contour of said frame into aligned ridge-like projections, whereupon these two outer ridge edges are then further bent toward each other to constitute the respective inturned lips or edges 9' and 9''. The inset strip 4 is made to span the gap between these inturned edges and subtend said bow profile. The innermost longitudinal edge 9' is shown fully clinched down upon the strip 4 while the outermost edge 9'' may only be partially clinched down and disposed on an incline to make an acute angle with respect to the face of the strip 4. Said lip 9'' may also be fully clinched down against the inset strip if so desired, but in either case, this partially or wholly clinched lip is intended to be nested within a recess or groove 3''' formed in the inner frame 3 and to co-act therewith to effect a snubbing action with respect to the interposed curtain fabric 2'' in a manner that will be more fully set forth presently. It will be observed that the innermost longitudinal edge 9' is adapted to overlap and grip the margin of the outer side of the pane 1.

The endless inner frame 3 and the endless dished outer frame 9 are detachably connected together preferably by a plurality of tapered screws 5 which screws loosely enter plain spaced openings in said inner frame 3 and engage their respective registering apertures formed in the inset strip 4 of the outer frame 9; the marginal portions of the apertures are given a peculiar formation in that each is provided with a suitable struck up or pressed up thread-like distortion adapted to receive and engage its respective tapered screw without resort to a conventional tapping of the strip 4 or to the use of self-tapping screws or such other means requiring the separate shaping up of each of the screw receiving apertures. It will be seen therefore that a further important feature of the present screw fastening means resides in initially so distorting or shaping up the metal edge around the screw apertures in the strip 4 as to constitute a threaded socket portion adapted to readily receive and engage said tapered screws, but all without requiring any substantial self-tapping action on part of the screws. The described simultaneous striking up or pressing up of all said thread formations in the relatively thin sheet metal is preferably performed by means of a stamping press while the inset strip 4 is still in the process of fabrication, as will readily be understood.

The screws 5, being tapered, the threads thereof cause the two frames to be tightly sprung together when the screws are drawn down into place.

The inner frame 3 and the inset strip 4 are each provided with flat abutting surfaces 3', 4', respectively where the screws connect them so that the frames may be drawn toward each other and impart the requisite tension upon the margin of the pane. The curtain fabric 2'' is disposed along the concealed face of the inner frame 3 and the pointed screws 5 serve to pierce through said fabric. The fabric may continue down to the inner edge of frame 3 as shown at 2' to be interposed between the frame and the pane.

The inner frame 3 is provided with an offset flanged part 3'' of rectangular profile adapted to clear the margin of the pane 1 and to cause the pane-gripping edge of said frame to exert its pressure against the pane along a line disposed inwardly from the margin of the pane, thus preventing the gripping action from tending to chip or break the pane. This rectangular flanged part 3'' essentially comprises two legs of which one constitutes an endless shoulder element disposed substantially normal to the face of the pane and adapted to center the edge thereof while the other leg of said profile serves as the internal gripping flange for the inner face of the pane and this element is slightly inclined away from the face of said pane so as to impart augmented resiliency to the set of complementary frames clamped about the margins of said pane.

If desired, the inset strip 4 may be provided with a corrugation 4'' extending, generally, to the corrugation 3''. A packing 6 is preferably contained in the corrugation 4'', as shown in Figs. 2 and 3, said packing bearing on the pane 1 and cushioning the gripping action as well as tending to render the joint more nearly water tight. If such a packing be interposed between the endless strip 4 and the face of the pane 1, it may be solid or tubular and is, preferably, of rubber having a certain degree of elasticity and compressibility with respect to the rigid pane.

As shown in Fig. 4, however, the packing 6 may be dispensed with and the gripping action of the clamped frames is then solely applied along the inner margin of said frame and inwardly of the outer margin of the pane.

The inset strip 4 is further provided with the flat surface portion 4' and if desired this may be equipped with struck-up or integral tongues or stops 7 which overlie the margin of the pane 1 and constitute spaced abutments for centering the outer frame 9 with respect to the pane; several of

these stops 7 are provided and they are intended to pierce the fabric. The inner frame 3 is provided with indented parts or cavities 8 which are adapted to receive the 5 lips or stops 7, thus accommodating the thickness of the said stops or lips without interfering with the position and clamping action of the inner frame 3. The supplementary pane centering stops 7 are not essential elements and may be dispensed with, 10 since suitable means for properly centering the complementary frame members with respect to the pane have been otherwise provided for in connection with frame 3.

15 Referring in further detail to the structure of the inner frame 3, the endless centering shoulder element 3'' thereof is equipped with an integral narrow flat face 3' disposed outwardly and around said shoulder 20 and this surface is adapted to abut against the annular flat face 4' of the inset strip 4. The outermost edge of the annular surface 3' is further provided with an integrally disposed groove or recessed corrugation 3''' 25 which is given a profile of such shape as to snugly receive and hold the inturned longitudinal edge 9'' of the outer frame in a nested relation when the two frame members are firmly clamped together about the interposed fabric 2'' by means of tapered screws 30 such as 5. The endless recess 3''' terminates in a circumscribing flange portion 3'''' which serves to bring the contour of the inner frame into substantial alignment with 35 the plane of the curtain fabric 2 and provides for a smooth rounded edge for the entrance of the fabric into the complementary frame members.

The endless outer finishing or ornamental 40 frame 9 may be of any suitable exterior form, but this frame is preferably made bowed in cross sectional profile in the manner described. The outer edge 9'' of the frame 9 is preferably made of such shape 45 and inclination that it presses the fabric 2 firmly into the nested endless recess 3''' as shown at 2'' when the parts are secured together as shown in Figs. 3 and 4. The circuitous path given to the fabric at 2'' and 50 the pressure of the inturned edge 9'', in connection with the sharp bend of the recess 3''' effects a gripping or snubbing action which minimizes the possibility of fabric 2 slipping, puckering, or pulling out and 55 as a result, the frames are very securely connected to the fabric and by this means the invention eliminates what has heretofore been a very troublesome defect in pane holding frames for automobile curtains. Furthermore, that this gripping or snubbing 60 action exists all the way around the frames and thus prevents any tearing of the fabric 2 due to the jerks and flappings to which curtains are subject.

65 It is pointed out that the particular type

of detachable tapered screws disclosed in connection with Fig. 4 constitute a further important feature of the present invention. The conventional round headed wood screw, preferably case hardened, may be used to 70 advantage for this purpose. As indicated in Fig. 2, a plurality of such screws may be suitably spaced about the contour of the clamped frame members with the head thereof of exposed and made accessible from the 75 inside of the curtain fabric. The narrow flat surface 3' of the inner frame is provided with a plurality of holes through which the tapered screw shank may be freely entered while the abutting flat surface 4' 80 of the inset strip is equipped with registering apertures struck or pressed up into suitable thread-like distortions adapted to engage said screw shank. The screw heads span said openings in the flat surface 4' and 85 shoulder against the respective edges of said holes, thereby drawing the flat frame parts together and properly clamping the separable frames about the pane.

The novelty and advantage of utilizing 90 said tapered screws partly lies in the fact that such wood screws are not only pointed but are ordinarily provided with an exceptionally coarse tapered thread for any given diameter, particularly so in smaller sizes 95 such as are used for present purposes. The pitch between the threads of wood screws is far greater than that of the corresponding size of the commercial machine screw and as a result the thickness of the sheet metal 100 is allowed to freely drop and wedge between the coarser tapered threads and securely engage therewith without thread interference. The tapered threads not only better adjust 105 themselves to the screw receiving aperture but provide for a more substantial grip to the thin sheet metal of the inset strip 4 than is afforded by the conventional threaded machine screw under these conditions.

The point on said wood screw is also 110 adapted to readily pierce the interposed fabric 2' and facilitates the finding of the blinded strip aperture which is initially concealed behind the fabric, all of which materially reduces the time and expense required to assemble the curtain window installation. Heretofore the use of the required large number of machine screws for fastening the curtain light frames together has proven a rather objectionable feature 115 when employed on a large scale production and assembly basis, primarily because of the excessive time element and the extra expense connected with the use thereto. The described tapered wood screw overcomes this 120 defect and otherwise serves to improve the detachable securing means for the complementary pane frame.

I claim:

1. In a set of separable sheet metal frame 130

- members adapted to encompass and hold a pane therebetween, a cross-sectionally bowed outer frame having both of its longitudinal edges inturned of which the innermost edge 5 overlaps the margin of one side face of the pane, an inset strip adapted to span and be clinched between the respective inturned edges of the outer frame and having a shoulder corrugation adapted to center the edge 10 of the pane, an inner frame adapted to overlap the margin of the opposite face of the pane, said last-named frame being provided with an integral shoulder corrugation adapted to center the edge of the pane and 15 with an endless recess spaced from said shoulder and adapted to receive and nest said inturned outermost edge of the outer frame, and means for fastening the frame members about the pane.

20 2. In a set of separable sheet metal frame members adapted to encompass and hold a pane therebetween, a cross-sectionally bowed outer frame having both of its longitudinal edges inturned of which the innermost edge 25 overlaps the margin of one side face of the pane, an inset strip adapted to span and be clinched between the respective inturned edges of the outer frame, said strip being provided with spaced screw receiving apertures having their respective marginal edges struck up or pressed up into thread-like 30 distortions, an inner frame adapted to overlap the margin of the opposite face of the pane, said last named frame being provided 35 with an endless recess adapted to receive and nest said outermost inturned external edge of the outer frame, and tapered screw means 40 fastening the inner frame member to the inset strip and serving to hold the complementary frames in engagement about the pane.

3. A curtain window installation comprising a combination, an endless cross-sectionally bowed sheet metal outer frame having both of its longitudinal edges inturned of which the innermost edge is adapted to 45 overlap the margin of one side face of the pane, an inset strip provided with screw receiving apertures initially struck up to 50 constitute thread-like distortions about their respective marginal edges, said inset being adapted to span and be clinched between the respective inturned edges of said outer frame, an inner frame adapted to overlap 55 the margin of the opposite face of the pane, said inner frame being provided with a plurality of holes therethrough registering with said apertures in the strip, and tapered screw means 60 freely entered through said holes and engaging said respective distorted apertures, the points of said screws being protected by and concealed within said bowed portion of the outer frame.

4. A curtain window installation comprising a combination, an endless cross-section-

ally bowed sheet metal outer frame having both of its longitudinal edges inturned of which the innermost edge is adapted to overlap upon the margin of one side face of the pane, an inset strip provided with screw receiving apertures initially struck up or pressed up to constitute a thread-like distortion about their respective marginal edges, said inset being adapted to span and be clinched between the respective inturned edges of said outer frame, an inner frame adapted to overlap the margin of the opposite face of the pane, said inner frame being provided with a plurality of holes therethrough registering with said apertures in the strip, a curtain fabric interposed between the inset strip and the inner frame, and tapered screw means entered through said holes and piercing the fabric to engage the respective distorted apertures in said strip, the points of said screws being protected by and concealed within said bowed portion of the outer frame.

5. In a set of separable sheet metal frame members adapted to encompass and hold a pane therebetween, a cross-sectionally bowed outer frame having both of its longitudinal edges inturned of which the innermost edge is adapted to overlap the margin of one side face of the pane, an inset strip clinched between said inturned edges to constitute an annular flat surface subtending said bowed portion of the outer frame, a plurality of spaced screw receiving apertures being provided in said surface of the strip, an inner frame adapted to overlap the margin of the opposite face of the pane, an endless centering shoulder for the inner frame disposed substantially normal to the face of the pane and adapted to center the edge thereof, an integral flat surface being provided on the inner frame disposed around said centering shoulder and adapted to about said flat surface of the inset strip, a plurality of holes being provided in said flat face of the inner frame registering with said apertures in the inset strip, and headed screw fastening means, the threaded shanks of which freely enter said holes and engage said apertures while the screw heads shoulder against the respective edges of said holes to draw the frame members against the pane.

6. In a set of separable sheet metal frame members adapted to encompass and hold a pane therebetween, a cross-sectionally bowed outer frame having both of its longitudinal edges inturned of which the innermost edge is adapted to overlap the margin of one side face of the pane, an inset strip clinched between said inturned edges to constitute an annular flat surface subtending said bowed portion of the outer frame, a plurality of spaced screw receiving apertures being provided in said flat surface of the strip, an

- inner frame adapted to overlap the margin of the opposite face of the pane, and having an endless centering shoulder disposed substantially normal to the face of the pane and adapted to center the edge thereof, an integral flat surface being provided on the inner frame disposed around said centering shoulder and adapted to abut said flat surface of the inset strip, a curtain fabric interposed between said flat surface of the strip and that of the inner frame, a resilient packing interposed between the inset strip and the margin of the pane, a plurality of holes being provided in said flat face of the inner frame registering with said aperture in the inset strip, and pointed screws serving to pierce the fabric, said screws being adapted to engage said apertures and clamp said fabric and simultaneously hold the respective frames with said interposed packing against the pane.
7. In a window installation comprising separable frame members adapted to hold a pane therebetween, a cross-sectionally bowed or dished sheet metal outer frame provided with an inset element having a screw receiving aperture initially struck up

or pressed up to constitute a thread-like distortion about the marginal edge thereof, an inner frame provided with a hole therethrough aligning with said aperture, and a tapered screw means entered through said hole and adapted to engage said distorted aperture, the point of said screw projecting through said inset and being concealed within said bowed portion of the outer frame.

8. In a curtain light comprising separable frame members adapted to hold a pane therebetween, an outer frame provided with a sheet metal inset having a plurality of screw receiving apertures each initially struck up or pressed up to constitute a thread-like distortion about the marginal edge thereof, an inner frame provided with holes respectively registering with said apertures, a curtain fabric interposed between the pane and one of said frames, and screw fastening means entered through the holes and the fabric and adapted to engage their respective distorted apertures in said inset.

In testimony whereof I affix my signature.

DANIEL M. WINANS.
